H. J. MOORE.
SOFT TURNDOWN COLLAR.
APPLICATION FILED SEPT. 13, 1921.

Patented Nov. 28, 1922.

Inventor

Harold J. Moore
By Lewis S. Clarkson
Attorney

UNITED STATES PATENT OFFICE.

HAROLD J. MOORE, OF MIDDLETOWN, CONNECTICUT, ASSIGNOR, BY DIRECT AND MESNE ASSIGNMENTS, TO GEO. P. IDE & COMPANY, INC., OF TROY, NEW YORK, A CORPORATION OF NEW YORK.

SOFT TURNDOWN COLLAR.

Application filed September 13, 1921. Serial No. 500,276.

To all whom it may concern:

Be it known that I, HAROLD J. MOORE, a citizen of the United States, residing at Middletown, in the county of Middlesex and 5 State of Connecticut, have invented certain new and useful Improvements in Soft Turn-down Collars, of which the following is a specification.

Soft turn down collars are usually made 10 from a number of separate distinct plies of material which are sewed together at their edges, the plies of the neck band and the plies of the fold over top portion being also stitched together at their upper edges.

15 Soft turn down collars have also been made of multiply interwoven material.

The object of my invention is to provide 20 a soft turn down collar made from multiply interwoven material of a particular weave which imparts to the collar certain inherent advantages not possessed by collars of multiply interwoven fabric heretofore produced.

A further object of my invention is to 25 produce a soft turn down collar made from multiply interwoven fabric wherein the neck band of the collar is woven with a greater number of warp threads than the fold over top portion, and wherein the top edge portion of the neck band is provided 30 with a greater number of warp threads than any other portion of the collar, thereby forming a guide for the fold line of the collar.

35 My invention consists of a soft turn down collar having a neck band and a fold over top portion, the neck band being stiffer than the turn down top portion, the upper edge portion of the neck band being thicker or 40 stiffer than the remaining portion of the neck band.

I do not herein claim the particular fabric from which my collar is made, inasmuch as it forms the subject matter of another application for patent to be filed by me September 13, 1921, Serial No. 500,277.

In the drawing:

Figure "1" is a plan view of the collar embodied in my invention, flattened out.

Figure "2" is a large detail vertical sectional view of my collar, folded.

The reference number "1" designates the neck band of my improved collar, the lower portion of which is of a certain number of

plies interwoven with each other, while the upper edge portion, "2," is formed with additional warp threads interwoven one with the other.

The top or turn down portion, "3," is of multiply interwoven fabric having a less number of plies than the neck band or the top edge portion of the neck band.

Multiply interwoven fabric has been found to be well adapted to the manufacture of collars, and with the variations of thickness or stiffness of the fabric as disclosed in this and the companion application, there is produced a fabric that is particularly well adapted for the manufacture of collars, inasmuch as the neck band is thicker or stiffer than the turn down portion, and in addition to this, the upper edge portion of the neck band is thicker or stiffer than the balance of the neck band and the turn down portion, so that the top portion will break or fold over at its juncture with the thickened top edge portion of the neck band. From this it will be seen that the thickened top edge portion of the neck band functions as a guide line for the proper folding of the collar.

Another advantage of the thickened top edge portion of the neck band is that it causes the fabric to bend in a graceful and curved line without material buckling or wrinkling, thus giving a much neater appearance to the collar.

Still another advantage of this increased thickness of the top edge portion of the neck band is that it spaces the turn down portion from the neck band at the top of the collar.

While I have shown a definite number of warp threads for the neck band and its top edge portion and the turn down portion, it would be understood that the number of warp threads may be varied according to the wishes of the manufacturer, so long as the top edge portion of the neck band has a greater number of warp threads than the other portions of the collar.

What I claim is:

1. A soft turn over collar having a neck band and a turn down portion made from a single piece of multiply interwoven fabric, the neck band being stiffer than the top folding portion, and having an integral

thicker extension at its top edge connecting the turn down portion with the neck band.

2. A soft turn over collar having a neck band and a turn down portion made from

5 a single piece of multiply interwoven fabric, the neck band having a greater number of interwoven warp threads than the turn

down portion and the top edge portion of the neck band having a greater number of interwoven warp threads than the body of 10 the neck band.

In testimony whereof I affix my signature.

HAROLD J. MOORE.
